UNITED STATES PATENT OFFICE

JOSEPH W. BELT, OF WEST CHESTER, PENNSYLVANIA

TIME CONTROLLED SWITCH

Application filed January 18, 1930. Serial No. 421,861.

This invention relates to electric time switches, and more particularly to such switches as are used in connection with the burners of heating plants.

5 The principal object of the invention is to provide a switch of this character in which the electric current will be turned on for a period covering a certain percentage of each hour, but which period will be divided into 10 several equal parts, distributed throughout the hour.

A further object is to provide a switch of this character wherein the On and Off periods may be adjusted to suit the conditions.

15 Other objects and advantages will be apparent from the following description when taken in connection with the accompanying drawings.

20 In the drawings:

Figure 1 is an elevation of a portion of a clock equipped with the circuit closer.

25 Figure 2 is an elevation of the rotatable contact plate located behind the dial, with the fiber plate carrying said contact plate.

Figure 3 is a sectional view on the line 3—3 of Figure 1, taken longitudinally of one of the slots in the clock dial.

Figure 4 is a vertical sectional view on the 30 line 4—4 of Figure 1.

Figure 5 is an elevation of a portion of a clock, wherein the three wire system is used.

Figure 6 is an elevation of the rotatable 35 plate showing the contact members, and their connections.

Referring particularly to the accompanying drawings 10 represents the cabinet of a clock, which has the dial 11, provided with the central circular opening 12, and behind 40 which is located the sheet of insulation 13. This sheet of insulation has the central opening 14, for the arbors of the hour and minute hands 15 and 16, of the clock, the openings 17 45 and 18, for the winding stems of the striker and movement of the clock, and the arcuate slots 19, for a purpose which will presently appear herein. Mounted on the arbors of the 50 clock is a fiber disk 20, which has a handle 21 extending outwardly through the side of the

cabinet. Secured to the outer face of the fiber disk 20 is a metal plate 23, preferably of brass, having the three radiating segmental portions 24. The disk 20 is so located, and the metal disk or plate, is so positioned 55 on the fiber disk, that arcuate portions of the face of the plate 23 will appear through the arcuate slots 19, as clearly seen in Figure 1. Attached to the side wall of the clock cabinet, adjacent the slot through which the handle 21 projects, is a plate 25, over which the handle 21 moves, said plate having markings thereon indicating the amount of time the switch is to be closed.

Secured to the minute hand 16, in position 60 to wipe along the faces of the portions of the plate 23, which are exposed through the slots, 19, is the contact brush 26. In one side of the cabinet of the clock are secured the electric terminals 27 and 28, the former of which is 65 connected or grounded on the metal frame of the clock movement, to bring the hand 16 into the circuit, while the other terminal is connected with the metal plate 23, by means of the wire 29. Other wires 30 and 31 are 70 connected with the terminals 27 and 28, and with any suitable source of electric current, not shown, and in which circuit is also arranged the valve controlling the flow of oil 75 to the burner of the heating system, but not 80 shown.

As shown in the accompanying drawings, the arcuate openings 19 are each of a length equal to the distance between three adjacent numerals on the clock dial, such distance representing the period of time in which the minute hand travels from one numeral to the third numeral therefrom, around the dial, which in the present instance is ten (10) minutes. During this period, the brush 26 contacts, successively, as the hand 16 traverses the dial, with each portion of the metal plate 23 which is exposed through the slot 19, and completes the circuit which causes the operation of the mechanism for opening the 90 burner. At the expiration of this period of contact, the brush passes from the metal plate onto the face of the insulated sheet 13, remaining in contact therewith, so as to maintain the circuit open, and the burner ex- 95 100

tinguished, until the brush drops through the next slot 19, into contact with the plate 23 thereunder, thus putting the burner in operation again. It will be noted that there are three of these slots 19.

Assuming that the operator desires the heating system to be in operation for 25% of the twenty-four hours, and off for the remainder, or 75%. This would mean that the burners would be on for fifteen minutes of each hour, and extinguished for forty-five minutes of each hour. The operator moves the handle 21 until it is opposite the numeral "25", which represents twenty-five percent of the twenty-four hours. This rotates the members 20 and 23 to expose such portions of the metal plate 23, through the three slots 19, as will total twenty-five percent, or one-fourth of the path of the minute hand 16 of the clock, or a total of fifteen minutes of each hour. Movement of the handle 21, to the numeral "50," on the plate 25, will rotate the metal plate 23 into position where the sum of the portions exposed through the three slots 19 will total one-half an hour, or 50% of the hour. On the other hand, the handle may be moved to the "15", so that the plate 23 will be exposed to represent a period of 15% of an hour. Thus the operator can set the clock carried device to govern the period at which the burner will be on, so that the greatest efficiency, with the highest economy, will result.

The foregoing represents the system where two wires are used, and is shown in Figures 1 to 4, inclusive. When, however, a three wire system is used, the form of the device, shown in Figures 5 and 6 is employed.

In the form shown in Figures 5 and 6, the clock dial 30 is provided with the arcuate slots 31, similar to those of the other form, and arranged in the same positions. Mounted to rotate behind the dial is a fiber disk or plate 32, having a handle 33 extending out through the side of the clock cabinet 34, as in the other form, to permit rotation of said plate. Secured to the outer face of the dial 30, adjacent one end of each of the slots 31, and transversely thereof, is a short wire contact member 35, the same being connected, at the back of the dial, by the wire 36, which leads to the binding post 37. Similar wires 38 are secured on the outer face of the disk 32, at regularly spaced intervals, and so positioned as to be exposed at different points along the slots 31. Each slot 31 is of a length equal to the distance between two of the hour numerals of the dial, and marked on the face of the dial, at one side of the slot, are numerals from 1 to 10, representing a ten minutes space on the dial, it being understood that the disk or plate 32 may be rotated to position each of its contact wires 38 opposite one of said numerals. These numerals represent minutes, and the distance between

one of the contacts 35, and the adjacent contact 38, represents the number of minutes between engagement of one by the hand carried brush 26', and engagement of the other by said brush.

The contacts 38 are connected similarly to the contacts 35, by means of the wire 39, which wire leads to, and is connected with the binding terminal 40. A wire 41 leads from the binding terminal 42, and constitutes the third, or common return wire of this three wire system. Connected respectively to the terminals 37, 42, and 40, are the conduits 43, 44, and 45, which lead to the mechanism to be operated, but which is not shown. It will be understood that, in one instance the wire 43 and 44, form one circuit, to produce the operation of the desired mechanism, while in another instance, the wire 45, and the wire 44, form another circuit, to produce a different operation of the same mechanism, although these two circuits may operate two different mechanisms, if desired.

What is claimed is:

1. The combination with a clock having a dial provided with a central opening, an insulated plate fixedly supported behind said dial and having a series of arcuate slots visible through said dial opening, a scale mounted on a side of the clock, an insulated plate on which is mounted a segmental metal plate rotatably mounted behind said slotted plate and having a handle extending through a side of the clock and arranged to traverse said scale, and a wiping contact supported by the minute hand of the clock for wiping over the face of said insulated plate, and over the metal plate through said slots.
2. The combination with a clock having a dial provided with a central opening, an insulating plate behind the dial and having openings therein, an insulated disk rotatable behind said insulating plate, contact members on the disk exposed through said plate openings, said disk being arranged to be moved to dispose the contacts thereof at different points with relation to the plate openings, and circuit closing means for successively engaging said contacts.

In testimony whereof, I affix my signature.

JOSEPH W. BELT.
